J. McLEAN.
FENCE ORNAMENT.

No. 19,773.

Patented Apr. 22, 1890.

UNITED STATES PATENT OFFICE.

JOHN MCLEAN, OF BROOKLYN, NEW YORK.

DESIGN FOR A FENCE ORNAMENT.

SPECIFICATION forming part of Design No. 19,773, dated April 22, 1890.

Application filed March 21, 1890. Serial No. 344,833. Term of patent 7 years.

To all whom it may concern:

Be it known that I, JOHN MCLEAN, a citizen of the United States, residing at Brooklyn, in the county of Kings and State of New York, have invented and produced a new and original Design for an Ornament for Fences, of which the following is a specification, reference being had to the accompanying drawing, forming part thereof, which represents my new design for an ornament for fences.

This invention relates to a new shape and surface ornamentation of an ornament for

fences and the like, the same being composed of the leaf-like end clusters *a a*, having between them the bulging center piece *d*, on which are ornamental rosettes *e e*, as shown.

What I claim is—

The design for an ornament for fences, &c., the same having the shape and surface ornamentation herein described and shown.

JOHN MCLEAN.
